UNITED STATES PATENT OFFICE.

AMBROGIO TURATI, OF TURIN, ITALY.

MACHINE FOR SPINNING COTTON AND OTHER TEXTILE MATERIALS.

Application filed October 10, 1927, Serial No. 225,245, and in Italy December 18, 1926.

In continuous ring spinning machines there is found this grave inconvenience:

When the roving is threaded through the aperture in the roving guide it often happens 5 that after having passed under the pair of rear cylinders it is not seized by the pair of intermediate cylinders on account of the deviations of its extremity, it winds itself upon the rear grooved cylinder or upon the lower 10 cleaner (when one is used).

To prevent this inconvenience the worker has to assist underneath with her fingers, the introduction of the roving between the pairs 15 of cylinders (and that is only possible when there is no cleaner) or to raise the back pressure cylinder in order to be able to assist upwardly with her fingers the introduction of the roving.

By acting in this manner the following in- 20 conveniences are caused:

1. Loss of time of the worker who is prevented from paying better attention to her work which results in a larger amount of loss and waste.
25 2. The worker can easily break the threads with her arm when seeking to assist the introduction of the roving from below.
3. The size and twist of the thread is irregular when the worker raises the back 30 pressure cylinder for the drawing off between the second and third pairs of cylinders being suppressed, the other thread which passes between these pairs (if not broken as occurs very often) becomes for the length of a few 35 meters, thicker and in consequence more twisted.

If this thread breaks there is the inconvenience of having to attach two threads instead of one. This defect is still more noticeable if the amount drawn off between the 40 pairs of back cylinders is considerable as is the case in modern spinning machines.

Moreover when the roving winds itself up considerably on the back grooved cylinder, 45 there are irregularities in the size and twist of the thread because the pressure cylinder being unable to press properly on the lower grooved cylinder, the attached roving enters, without being drawn off, between the pair of 50 front cylinders; in addition sometimes the roving also becomes entangled in the little supports of the grooved cylinders which under the effort vibrate causing serious damage, especially when working fine or loosely twisted 55 ed yarns.

The apparatus, forming the object of the

present invention prevents all these inconveniences because by its employment, the roving threaded through the hole of the roving guide, after it has passed, without any need 60 of being assisted by the worker, under the back cylinder, is always seized by the intermediate cylinders.

Such an apparatus consists substantially in a bridge piece suspended by side arms from 65 the pivots of the back pressure cylinder the central portion of which bridge extends between the two rear and intermediate grooved cylinders to support and guide the roving.

In the accompanying drawing is represented, by way of example, a form of construction of the apparatus forming the object of the present invention.

Fig. 1 shows in perspective this apparatus and the back pressure cylinder from the pivots of which it is suspended.

Fig. 2 shows a transverse section of the apparatus applied to the spinner.

1 indicates the rear pressure cylinder from the pivots of which is suspended the apparatus 80 2, comprising two lateral arms 2^a the extremities of which are mounted on the pivots of the cylinder 1 and a central part 2^b constituting the surface for supporting and guiding the roving in its passage from the 85 rear grooved cylinder 4 to the intermediate grooved cylinder 5 placed under the intermediate pressure cylinder 6.

The surface 2^b is then parallel to the bed 3 of the spinner and tangential or nearly so 90 to the grooved cylinders 4 and 5 between which it extends in the form of a bridge.

The surface 2^b of the apparatus is provided at both sides at its central part with projections or teeth 2^c and 2^d pressing against the 95 central smooth part of the grooved cylinders 4 and 5, which prevents the edges of the surface 2^b from running against the grooves of the said cylinders whilst they hold the apparatus in its exact position for working.

Claims—

1. In a ring spinning machine, the combination with a rear pressure cylinder, and rear and intermediate grooved cylinders, of a bridge piece suspended from the pivots of the pressure cylinder and extending between the rear and intermediate cylinders substantially tangential to said cylinders and adapted to support and guide the roving in its passage between the pair of rear cylinders and the 110 pair of intermediate cylinders.

2. In a continuous ring spinning machine,

the combination with the rear pressure cylinder and the rear and intermediate grooved cylinders, of a bridge piece extending between the rear and intermediate cylinders and
5 forming a supporting and guiding surface for the roving substantially tangential to said cylinders, said bridge piece having projections cooperating with the rear and intermediate grooved cylinders to hold the edges of
10 the bridge piece in operative relation to the cylinders.

3. In a continuous ring spinning machine, the combination with the rear pressure cylinder and the rear and intermediate grooved

cylinders, of a bridgepiece comprising a central portion forming a guide for the roving and having lateral arms connected to the axle of the pressure cylinder to support the central portion substantially tangential to the cylinders, said central portion having projections on opposite edges engaging central smooth portions of the grooved cylinders whereby the bridge piece is maintained in operative relation to the cylinders. 15
